UNITED STATES PATENT OFFICE.

FRANK W. LAW, OF PITTSBURG, PENNSYLVANIA.

DESIGN FOR A GAS-BURNER.

SPECIFICATION forming part of Design No. 28,803, dated June 7, 1898.

Application filed March 26, 1898. Serial No. 675,193. Term of patent 14 years.

To all whom it may concern:

Be it known that I, FRANK W. LAW, a citizen of the United States, and a resident of Pittsburgh, in the county of Allegheny and State of Pennsylvania, have invented a certain new and original Design for Gas-Burners, of which the following is a specification, reference being had to the accompanying drawings, forming part thereof, in which—

10 Figure 1 is a face view or front elevation of a gas-burner embodying my design, and Fig. 2 is a cross-section thereof.

The leading feature of my design consists in a gas-burner having a face-plate with rows 15 of perforations therein extending across the face-plate in semicircles. Each end of the semicircles in the rows meets in the center of the semicircles of the next row to form rows of spaces which are filled with woolly fiber.

20 As shown in the drawings, *a* represents the face-plate of the burner, having a series of perforations *b* therein. These perforations

b are formed in semicircles *c*, extending across the face-plate *a* to form rows *d*, and each one of the rows *d* is adapted to break joint with each other. The vertical center line of each one of the semicircles *c* in the rows *d* meets the ends of the semicircles *c* of the next rows *d*, so as to form rows of spaces *e*, having semicircular tops *f* and pointed lower ends *g*, 25 formed by the quarto-circles *h* of the next rows *d*. Woolly fiber *i* is inserted on each one of the spaces *e*.

I claim—

The design for a gas-burner, substantially 35 as herein shown and described.

In testimony whereof I have hereunto set my hand, at Pittsburgh, in the county of Allegheny and State of Pennsylvania, this 23d day of March, A. D. 1898.

FRANK W. LAW.
